UNITED STATES PATENT OFFICE

ALBERT JEFFERSON SAMS, OF CHICAGO, ILLINOIS

HYDRAULIC ADJUSTABLE HUB PLATE

Application filed January 23, 1929. Serial No. 334,497.

This invention aims to provide novel means whereby the hub plate of driving and other wheels of a locomotive engine, steam or electric, may be kept in contact with the corresponding bearings on the frame of the engine and leading and trailing trucks, it being possible to keep the hub plate advanced by means of pressure derived from an external source of pressure supply.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 is an elevation of a wheel equipped with a device constructed in accordance with the invention;

Figure 2 is a section on the line 2—2 of Figure 1;

Figure 3 is a section enlarged from Figure 2;

Figure 4 is an elevation of the valve casing;

Figure 5 is a plan of the abutment ring;

Figure 6 is a section of the abutment ring;

Figure 7 is a plan of the ram ring;

Figure 8 is a section of the ram ring;

Figure 9 is a plan of the hub plate;

Figure 10 is a section of the hub plate;

Figure 11 is a section on the line 11—11 of Figure 1;

Figure 12 is a view like Figure 1 but showing a modification;

Figure 13 is a section on the line 13—13 of Figure 12;

Figure 14 is a section enlarged from Figure 13;

Figure 15 is a plan of the cylinders;

Figure 16 is an elevation of the cylinders with the pistons withdrawn;

Figure 17 is a plan of the hub plate;
Figure 18 is a section of the hub plate;
Figure 19 is an elevation of one of the cylinders;

Figure 20 is a section of the cylinder; 55

Figure 21 is a sectional view showing a modification;

Figure 22 is an elevation of the hub plate;

Figure 23 is an elevation of the follower plate; 60

Figures 24, 25, and 26 are sectional views showing modifications.

In Figures 1 to 11, the numeral 1 marks the frame of a locomotive engine, carrying a bearing 2. An axle is shown at 3, and 4 designates the hub of a drive wheel 5 having an outer groove 6 and an inner groove 7 at the base of the outer groove. An annular hub plate 8 is slidably mounted in the groove 6 and has a flange 9 that overlaps the end of the hub 4. A dowel pin 10 engaged with the hub plate 8 and with the hub 4 holds the hub plate against rotation. A ram ring 11 is received in an annular recess 12 in the hub plate 8 and extends into the inner groove 7. An abutment ring 14 is seated in the groove 7 and has a cylindrical body 15 slidable in an annular chamber 16 in the ram ring 11, the chamber 16 forming a central projection 17 having a depression 18 in its end. 70

The body 15 of the abutment ring 14 has a roughened inner surface 19 that holds a packing 20 on the body portion 15, about the projection 17. 75

A nipple 21 is threaded into the hub 4 and has a head 22 that engages the abutment ring 14. 80

A passage 23 leads to the nipple 21 from an enlarged bore 24 in the hub 4. A valve casing 25 is threaded into the bore 24 and has a wrench head 26 that bears against the hub 4. There is a cage 27 on the inner end of the casing 25, and a ball check valve 48 works in the cage and cooperates with a tubular seat threaded into the valve casing 25 against a lip 29 at the inner end of the casing. 85

A closure plug 30 is threaded into the casing 25 and has a socket 31 to receive a tool 90

4

and has a head 22 that engages the abutment ring 14. 95

A passage 23 leads to the nipple 21 from an enlarged bore 24 in the hub 4. A valve casing 25 is threaded into the bore 24 and has a wrench head 26 that bears against the hub 4. There is a cage 27 on the inner end of the casing 25, and a ball check valve 48 works in the cage and cooperates with a tubular seat threaded into the valve casing 25 against a lip 29 at the inner end of the casing. 100

whereby the plug 30 can be removed. A nipple 32 is located opposite to the nipple 21 and communicates with a passage 33 opening into a chamber 34 in the hub 4, a closure plug 35 being threaded into the chamber.

In operation, the plugs 35 and 30 are taken out and any kind of grease pump or pressure device is threaded into the casing 25 in the place of the plug 30. When the grease begins to show at the chamber 34, the plug 35 is put back, and then the grease, under pressure, forces the ram ring 11 against the hub plate 8, and the hub plate 15 against the bearing 2. The check valve 38 holds the grease under pressure and keeps the ram ring 11 seated against the hub plate, and the hub plate against the bearing.

In Figures 12 to 20, parts hereinbefore 20 described have been designated by numerals previously used, with the suffix "a". The ram ring 11 and the abutment ring 14 are omitted, and their place is taken by a plurality of cylinders 36 located in the inner 25 groove 7 and connected by pipes 37.

Pistons 38 slide within packings 39 held 30 in the cylinders by the roughened surfaces 40 of the cylinders. All of the cylinders 36 are retained by nipples 21a. Three of the 35 nipples communicate by the passages 23a with the check valve mechanism 48a—25a, and the fourth nipple communicates by the passage 33a with the outlet chamber 34a that is closed by the plug 35a.

35 In this form of the invention, the pistons 38 are advanced under pressure to hold the hub ring 8a against the bearing 3a. The hub plate 8a may be made in sections, halved together as at 41.

40 In Figures 21, 22, and 23 there is shown a device of the class described, modified to some extent from the structures which have been described hereinbefore. The axle is shown at 60, and the hub of the wheel appears at 61. The hub 61 has an annular groove 62 in which the hub plate 63 is slidably mounted. The hub plate 63 has a flange 64 that overlaps the end of the hub 61. The hub plate 63 is transversely divided as shown at 65, to form sections, and the sections of the hub plate are tongued and grooved together, as at 66. At its inner corners, the hub plate 63 is cut away to form concaved seats 67.

45 The hub plate 63 is provided with a V-shaped groove 68, receiving a correspondingly shaped spreader ring 69, and packings 70 are located in the seats 67. The base of the spreader ring 69 rests against a sheet 50 of asbestos, or any other suitable packing composition, shown at 71, and the sheet 71, in its turn, abuts against a follower plate 72 which is divided and tongued and grooved together, as shown at 73. There is 55 an annular recess 74 in the hub 61 behind

the follower plate 72, and from the recess 74, a passage 75 leads, at an incline, to an enlarged bore 76, corresponding to the bore 24 of Figure 3, the numeral 77 designating a valve casing and corresponding parts, such as is disclosed in Figure 3. 70

When grease is forced through the passage 75 into the recess 74, the hub plate 63 will be advanced as hereinbefore described, the grease finding its way entirely around the hub, through the annular recess 74. The function of the spreader ring 69 is to insure pressure fit of the hub plate 63 being practically the same throughout the circumference. This is especially desirable in sectional applications where wheel hubs are bored with lathe, with wheels axled, where there is likely to be a slight variance from a true circle. 75

In practical operation it has been found 80 that the fit of the hub plate 63 in the groove 62 is not uniform in tightness throughout its circumference. The purpose of the V-shaped groove 68 and the correspondingly shaped spreader ring 69 is to expand or spread the hub plate sufficiently both toward the inside fitting surface and the outside fitting surface to overcome such imperfections in pressure fit as there may be. 85

In Figure 26, parts hereinbefore described 90 in connection with Figure 21 have been designated by numerals previously used with the suffix "b". In this form of the invention, the passage 75b is not inclined like the passage 75, but is disposed approximately at right angles to the recess 74b. 95

In Figure 24, parts hereinbefore described 100 have been designated by numerals previously used with the suffix "c". A seat 67c has a groove 78 in its base, and the packing 70c 105 is triangular in cross section with a V-shaped rib 79 that extends into the groove 78.

In Figure 25 of the drawings, parts hereinbefore described have been designated by numerals previously used with the suffix "d". The packing 70d is of circular cross section and is received in a correspondingly shaped seat 71d in the hub plate 63d, the hub 61d having a conical surface 80 with which the packing 70d engages. 110

Grease has been referred to hereinbefore, but it will be understood that any sort of hydraulic fluid may be employed. As a matter of fact, it is suggested that a recoil oil be employed as a hydraulic fluid, the oil 115 being of the sort used in connection with the recoil structure of pieces of artillery, an oil which will withstand very high temperatures, such as 365 degrees F. 120

The chief object of the adjustable hub plate is that it may be adjusted toward the bearing on the locomotive frame to take up excess lateral play between the driving box and the bearing face of the hub of the locomotive driving wheel. 125 130

The inspection department of the Interstate Commerce Commission requires that there shall be a limited amount of lateral or side play between these two bearings, and as a matter of information, it may be stated that the lateral limit is three-quarters of an inch between the two hubs on the same axle and the corresponding bearing boxes on the frame. Hence, the object of the adjustable hub plate is to enable the railroad using the locomotive to maintain the lateral play within the limit allowed by the Interstate Commerce Commission, the hub plates being adjusted as the wear on the hub plates and the driving box bearing faces takes place.

I claim:—

1. A wheel having a slidable hub plate, means for coupling a fluid pressure device to the wheel to put pressure on the hub plate, and means for temporarily relieving the pressure behind the hub plate at the beginning of the operation of the fluid pressure device, thereby to attain an even distribution of the pressure fluid behind the hub plate.

2. A wheel having a groove, the wheel having an inlet leading to the groove and an outlet leading from the groove, a hub plate slidable in the groove, a closure for the inlet, and a closure for the outlet, the closure for the inlet being removable for the attachment of the pressure device, and the closure for the outlet being removable to permit the exit of air and to facilitate a distribution of the pressure fluid upon the hub plate.

3. A wheel having a groove, an inlet leading to the groove, and an outlet leading from the groove; an outwardly closing check valve in the inlet, a removable closure for the inlet, and a removable closure for the outlet.

4. A wheel having a groove, a hub plate slidable in the groove, spaced cylinders in the groove, pistons slidable in the cylinders and cooperating with the hub plate to advance it, means for establishing communication between the cylinders, an outlet for one cylinder, and an inlet for another cylinder.

5. A wheel having a groove, a hub plate slidable in the groove, spaced cylinders in the groove, pistons slidable in the cylinders and cooperating with the hub plate to advance it, means for establishing communication between the cylinders, an outlet for one cylinder, an inlet for another cylinder, a removable closure for the inlet, a removable closure for the outlet, and an outwardly closing check valve in the inlet.

6. A wheel having a groove, a hub plate slidable in the groove, the hub plate having a V-shaped groove in its inner end surface, a correspondingly shaped spreader

ring in the groove, a follower plate engaging the spreader ring, and means for delivering pressure against the follower plate.

In testimony that I claim the foregoing as my own, I have hereto affixed my signature.

ALBERT JEFFERSON SAMS.
